UNITED STATES PATENT OFFICE.

WILLIAM SILVER, OF TAMWORTH, NEW SOUTH WALES.

RAILWAY-AXLE LUBRICATOR.

SPECIFICATION forming part of Letters Patent No. 588,247, dated August 17, 1897.

Application filed March 3, 1896. Renewed July 19, 1897. Serial No. 645,168. (No model.)

To all whom it may concern:

Be it known that I, WILLIAM SILVER, engineer, a subject of the Queen of Great Britain, and a resident of Tamworth, New South 5 Wales, have invented certain new and useful Improvements in Railway-Axle Lubricators, of which the following is a specification.

This invention relates to a self-contained lubricating device for railway-car axles. It 10 has been devised with the object of efficiently applying oil to the axle uniformly and continuously, preventing waste of oil, and providing a construction which will allow of the oil-reservoir and the swab being easily and 15 quickly cleaned and the reservoir refilled.

I make my lubricator entirely independent of the axle-box and adapt it to fit into such box in such a way that it can be readily withdrawn for cleaning or refilling and reset in 20 the box without loss of time.

For the purposes of my invention the interior of the axle-box is a simple cubical cavity carrying the brasses and provided with a hinged or bolted cover through which the 25 lubricator can be inserted and withdrawn. The lubricator is made to slide into the bottom of the axle-box, so that the swab will bear up against the axle.

The lubricator consists of a light metal reservoir whose top plate is dished downward toward the middle, where there is an orifice through which the swab dips into it. The swab is a T-shaped (or similarly-shaped) block of soft felt or other suitable spongy 35 fabric, and it is held in a yoke which is mounted on a pair of flat riding-springs whose ends bear on the top side of the reservoir, the yoke and springs forming a spring-seat for the swab. The lower part of the swab fills the 40 orifice in the reservoir, but is capable of sliding vertically in guides around said orifice and of moving about with ease to adjust itself, but so as not to leave any opening through which the oil could slop out. The riding-springs hold the top of the swab up against 45 the axle, but allow it to adjust itself so that it will bear constantly and evenly and apply an even film of oil to the axle. The sides of the oil-reservoir are continued up to form 50 side guards which catch any spray or drips of oil from the axle or brasses and direct them

into the reservoir, and end guards may also be provided.

The shape of the reservoir effectually prevents the oil from being slopped out, and as 55 the swab applies only a wiped film of oil to the axle there can be no drip or waste.

The oil-reservoir and swab can be lifted out of the axle-box and a duplicate complete lubricator inserted in a moment or a new swab 60 inserted, as may be required.

Referring to the annexed drawings, Figure 1 is a longitudinal section through a railway-axle box holding a lubricator constructed according to the present invention; Fig. 2, a 65 horizontal section and plan on line A B, Fig. 1; Fig. 3, a transverse section; Fig. 4, a longitudinal half-sectional elevation through the lubricator-box alone; Fig. 5, a plan of the same; Fig. 6, a transverse half-sectional elevation through same, and Fig. 7 an end elevation of swab-yoke and riding-springs. There is no novelty in the construction of the 70 box or bearings. Fig. 8 is a side view of the swab detached.

1 is the oil-reservoir, whose top plate 2 is dished downward from the outer part to the central orifice 3, at the sides of which cheeks or vertical guide-plates 4 are set, having a 75 number of holes 5 in their lower part to allow 80 any oil which may come on the top plate 2 to flow back in the reservoir through the orifice 3.

The plates 4 are rigidly secured to and carried by the dished top 2 of the oil-reservoir, 85 and this part may be cast or otherwise formed with its various parts.

The sides 6 of the reservoir 1 are continued up to form side splash or guard plates, and their top edges are turned in so as to come 90 close up to the sides of the brasses 7. The ends 8 of the reservoir 1 are also continued to form end splash or guard plates. These side and end plates catch any oil sprayed or thrown from the axle or brasses and cause it 95 to flow back into the reservoir 1, whereby oil waste is prevented and the box kept clean.

The yoke or swab-carrier consists of two side plates 9, connected together by transverse pieces 10 at the ends thereof outside the 100 ends of the swab, and, if desired, also a bottom loop 11. These hold the swab 12, which

is a rectangular piece of material the two lower corners of which are cut away to decrease the length of its lower part. Its upper part is as long as the brass, but the lower part 5 is only sufficiently long to fill the orifice 3. The swab can be pulled out of this yoke and reinserted very readily.

Brackets 13 on the plates 9 carry riding-springs 14, whose ends bear on the top plate 2 10 of the reservoir. The yoke fits between the plates so as to slide freely, and the depth of the swab is such that its lower part will be always in oil while the upper part is rubbing against the axle. The riding-springs are light 15 flat springs, which while bearing the swab constantly upward allow it to adjust itself to the axle so that it will bear for its full length.

15 is the door of the box, which must be opened when it is required to enter or with- 20 draw the lubricator.

It is evident that the shape of the reservoir 1 can be altered so long as the top plate 2 is so arranged that there will be a considerable 25 surplus space over the oil around the sides of the chamber, in which it can surge about, whereby splashing and slopping out of oil is prevented.

The arrangement of the riding-springs also might be varied. Thus they might be made

to bear on the end guards 8 instead of on the 30 top plates 2.

Having now particularly described and ascertained the nature of my said invention and in what manner the same is to be performed, I declare that what I claim is—

35

1. In combination, the casing, the oil-reservoir having the dished top with the central opening and with the upwardly-extending guides 4, the swab-carrier having the swab therein and having the lateral extensions lying over the dished top and the springs between the dished top and the lateral extensions, substantially as described.

40

2. In combination, the main casing, the reservoir having the dished top with the central opening and the guide-plates 4, the swab extending through the central opening of the reservoir, and means for carrying the same, said guide-plates 4 being perforated for the return of the oil to the reservoir, substantially 45 50 as described.

In testimony whereof I have signed my name to this specification in the presence of two subscribing witnesses.

WILLIAM SILVER.
